(57) **CLAIM**

What is claimed is an ornamental design for a virtual reality headset, as shown and described herein.

DESCRIPTION

FIG. 1 is a front perspective view of a virtual reality headset; FIG. 2 is a rear perspective view of the virtual reality headset shown in FIG. 1;

FIG. 3 is a front view of the virtual reality headset shown in FIG. 1;

FIG. 4 is a rear view of the virtual reality headset shown in FIG. 1;

FIG. 5 is a left-side view of the virtual reality headset shown in FIG. 1;

FIG. 6 is a right-side view of the virtual reality headset shown in FIG. 1;

FIG. 7 is a top-side view of the virtual reality headset shown in FIG. 1; and,

FIG. 8 is a bottom-side view of the virtual reality headset shown in FIG. 1.

Any broken lines in the drawing are for purposes of illustrating portions of the virtual reality headset and form no part of the claimed design.

1 Claim, 8 Drawing Sheets
